DESIGN FOR A DOLL HEAD

Calvin Harris Boughman, New York, N. Y.

Application January 3, 1948, Serial No. 143,531

Term of patent 3½ years

(Cl. D34—4)

To all whom it may concern:

Be it known that I, Calvin Harris Boughman, a citizen of the United States of America, residing at New York, in the county of New York and State of New York, have invented a new, original, and ornamental Design for a Doll Head, of which the following is a specification, reference being had to the accompanying drawing, forming part thereof.

In the drawing:

I claim:
The ornamental design for a doll head, as shown.

CALVIN HARRIS BOUGHMAN.
